Primary Examiner — Richard E Chilcot(57) **CLAIM**

The ornamental design for a tent frame, as shown and described.

DESCRIPTION

1. Tent frame

FIG. 1.1 is a perspective view of new design for a tent frame as shown in the drawings;

FIG. 1.2 is a front elevation view thereof;

FIG. 1.3 is a rear elevation view thereof;

FIG. 1.4 is a top plan view thereof;

FIG. 1.5 is a bottom plan view;

FIG. 1.6 is a left side view thereof; and,

FIG. 1.7 is a right side view thereof.
